UNITED STATES PATENT OFFICE.

OEN MEDARIS, OF BOISE, IDAHO.

ORE-SEPARATOR.

No. 921,427.

Specification of Letters Patent.

Patented May 11, 1909.

Application filed September 20, 1906. Serial No. 385,427.

To all whom it may concern:

Be it known that I, OEN MEDARIS, a citizen of the United States, residing at Boise, in the county of Ada and State of Idaho, have 5 invented a new and useful Ore-Separator, of which the following is a specification.

This invention relates more particularly to means for separating gold from the soil in which it is located, and the principal object 10 is to provide a simple structure of a novel nature that will effectively separate and conserve the gold, will successfully operate with a very small quantity of water, and is not liable to become choked or clogged with 15 the material from which the desired metal is secured.

The preferred form of construction is illustrated in the accompanying drawings, wherein:—

20 Figure 1 is a side elevation of the machine. Fig. 2 is a vertical longitudinal sectional view therethrough. Fig. 3 is a cross sectional view. Fig. 4 is a detail horizontal sectional view, showing the gearing for operating the concentrator belt. Fig. 5 is a detail perspective view of one of the aprons. Fig. 6 is a detail perspective view of a portion of 25 the water delivering means. Fig. 7 is a detail perspective view of one of the supports for the belt carrying frame. Fig. 8 is a detail sectional view on the line 8—8 of Fig. 1. Fig. 9 is a face view of the driving wheel for 30 the pump.

Similar reference numerals designate cor- 35 responding parts in all the figures of the drawings.

In the structure disclosed, a supporting frame is employed, comprising standards 10, upper and lower longitudinal beams 11, and 40 cross beams 12. Mounted on one end of the frame are grooved rollers 13, while other smooth faced rollers 14 are journaled on a bracket 15 that is located on an intermediate portion of the frame, and is vertically ad- 45 justable thereon. This bracket, as shown in Fig. 3, has depending legs 16, provided with upright slots 17, through which are passed holding screws 18 that are threaded into the upper beams 11. A rotary screen or grizzly 50 19 is supported on the rollers, and while for ordinary purposes, the screen may have a single wall, where the material to be separated is heavy and includes large rocks and the like, a double screen is preferably em-

ployed. Thus in the present embodiment, 55 an inner coarse screen 20 is surrounded by a finer screen 21, the inner screen inclosing a feeding coil 22 comprising a heavy rod or wire. The screen at one end has a hoop 23 provided with an annular outstanding flange 60 24 that engages in the grooves of the rollers 13. Another hoop 25 at the lower end of the screen rests upon the smooth faced rollers 14. The screen walls 20 and 21 at the lower end are held in spaced relation by spaced 65 webs 26, which permit the outflow of material that is fine enough to pass through the coarser screen 20 or too coarse to pass through the finer screen 21. A rearwardly extending arm 27, secured to the bracket 15, 70 constitutes a support for a swinging tailings discharge trough 28 that is located in rear of the lower end of the rotary screen, and has a depending pintle 29 at its upper end that is journaled in the rear end of the arm 27. By 75 this means, it will be evident that the trough may be placed, so as to deliver from either side of the machine, as desired. The material is fed to the screen by an inclined chute 30 that is located at its upper end, and is sup- 80 ported by suitable brackets 31.

Oppositely inclined aprons are located beneath the screens. As these aprons are substantially duplicates, a description of one is believed to be sufficient for both. 85 Each apron consists of an oblong frame 32, set at an inclination, and having the apron body detachably mounted thereon. This body includes a longitudinally disposed central bar 33 and sets of cross clamping bars 90 34, the said bars forming pockets, the cross bars constituting the end walls of said pockets. Horizontally disposed bottoms 35 are provided for these pockets, said bottoms being formed of sheets that extend on sub- 95 stantially the length of the bodies and are located and clamped between the cross bars of the different sets, as clearly shown in Fig. 2. It will be observed that the bottoms are horizontally disposed and each is located 100 in a plane lower than the one in advance of it. The pockets, thus produced, are very shallow, and the intermediate portions of the lower end walls project above the bottoms not over one-eighth of an inch. At 105 the corners, however, the end walls extend higher, being provided with substantially triangular projections 36. The purpose of

these projections is to prevent the too rapid passage of the heavy particles, for in operation, the aprons are shaken transversely, thus throwing said heavy particles to the sides. The lower end of the upper apron rests upon the upper end of the lower apron, and is provided with a discharge opening 37 delivering to such upper end. The lower end of the lower apron has a similar discharge opening 38 disposed over a downwardly inclined guide pan 39, fastened at its upper end, as shown at 40 to one of the cross bars of the frame, its lower end being suspended by links 41 secured to the upper side bars of the frame.

The aprons are relatively adjustable, and for this purpose, links 42 are provided, the said links being secured to the upper end of the upper apron and to the lower end of the lower apron. These links have openings 43 therethrough, through which are passed fasteners 44 that engage said lower apron. Thus the distance between the upper end of the upper apron and the lower end of the lower apron can be varied, so that their relative angle may be changed. The aprons are furthermore supported on upright leaf springs 45, the lower ends of these springs being located inside the lower side bars 11 of the frame, and being adjustably secured thereto by clamp plates 46 that extend across the springs and frictionally engage the same, being held in such frictional engagement by fasteners 47 passed through the clamping plates and into the side bars. Outstanding ears 48, carried by the lower apron, rest upon the upper ends of the springs. By this construction, it will be evident that the aprons are capable of lateral movement and are furthermore vertically adjustable.

The lower ends of the posts 10 have longitudinally disposed slots 49, in which are engaged clamping bolts 50. The heads of these bolts carry upright springs 51, on the upper ends of which rest outstanding ears 52, fastened to an oblong belt carrying frame 53. This frame is preferably located at an inclination, and is disposed below the guide pan 39. In its ends are journaled rollers 54, around which passes a concentrator belt 55, guide rollers 56 being employed to support intermediate portions of the upper stretch of the belt. The frame furthermore has depending central hangers 57, in which is journaled a guide roller 58. The concentrator belt 59 passes about the rollers 54 and beneath the guide rollers 58, which guide rollers maintain the central portion of the lower stretch of the belt within a pan 59.

A pump 60 is located at one corner of the frame, and the plunger thereof has a rod 61 that projects above the pump. A discharge pipe 62, extending from the pump, leads upwardly to the inlet end of the screen, and

has a discharge nozzle 63 projecting thereinto. A branch 64, from the pipe 62, extends transversely of the upper end of the belt 55, and is perforated, as shown at 65.

A driving shaft 66 is journaled on one side 70 of the frame, and may be operated by any suitable means, as for instance, a handle crank 67. A countershaft 68 is journaled on the same side of the frame below the shaft 66, and is connected thereto by sprocket gear- 75 ing 69. The ends of the countershaft 68, carry crank disks 70, and the pins 71 of said disks are connected to the aprons by pitmen 72. Another countershaft is located below the shaft 68, and comprises sections 80 73 and 74 connected by a universal joint 75. The section 73 is geared to the drive shaft 66 by sprocket mechanism 76. The section 74 is capable of a swinging movement, and its free end is journaled in a boxing 77. In this boxing is also journaled a shaft 78 extending from one end of one of the rollers 54 of the concentrator belt, and has a worm wheel 79 thereon. A worm 80, carried by the shaft section 74, coöperates with the worm wheel 90 79. The shaft section 73 is furthermore provided with cranks 81, which cranks are connected to the belt carrier frame by pitmen 82. The rear end of the driving shaft 66 has a crank wheel 83, provided with a radially disposed series of openings 84, in any of which the crank pin 85 may be placed, as shown in Fig. 9. A walking beam 86 is fulcrumed upon one end of the frame, and has a link connection 87 with the upper end of the piston or plunger rod 61, the other end of the walking beam having a pitman connection 88 with the crank pin 85.

In operation, the material is directed by the chute 30 into the screen, and is there subjected to a spray of water delivered by the pump 60 through the pipe 62 and nozzle 63. The smaller particles pass through the screen wall 20, while the heavier material is discharged into the trough 28. The material, which passes through the screen 20 is again graded by the screen 21, part being delivered into the tailings trough 21, the remainder falling upon the upper portion of the upper apron. This material passes over the amalgamator aprons, which are given a rapid transverse reciprocation, and from thence fall upon the pan 39. This pan may be of copper, but for ordinary purposes, sheet iron has been found entirely satisfactory. The material is finally delivered upon the belt 55, which belt is not only moved longitudinally by the driving means described, but is also given a rapid transverse shaking movement, inasmuch as the frame 115 carrying it is connected to the cranks 81 by the links 82.

It will be evident that this structure is comparatively simple, and experience has demonstrated that it is entirely effective in 130

operation, yet it is readily adjustable to suit the different characters of material that are operated upon, and furthermore may be easily set up, and the parts properly adjusted 5 to effectively perform their work. A comparatively small amount of water is needed to successfully operate the machine, and there is no danger of the aprons becoming clogged with material, inasmuch as the pockets are very shallow. The amount of water can be readily varied by varying the stroke of the pump, this being accomplished by placing the crank pin 85 nearer or farther away from the shaft that carries the crank wheel 83. The supply of water is thus regulated without altering the speed of the driving means.

From the foregoing, it is thought that the construction, operation, and many advantages of the herein described invention, will be apparent to those skilled in the art, without further description, and it will be understood that various changes in the size, shape, proportion, and minor details of construction, 20 may be resorted to without departing from the spirit or sacrificing any of the advantages of the invention.

Having thus fully described my invention, what I claim as new, and desire to secure by 25 Letters Patent, is:—

1. In a machine of the character described, the combination with a supporting frame, of a bracket having spaced depending legs vertically adjustable on the supporting frame, 30 means for holding the legs at different positions on the supporting frame, rollers journaled on the bracket, a screen having its lower end rotatably mounted on the rollers, an arm projecting rearwardly from the 35 bracket, a tailings receiving trough pivoted at its upper end on the arm in rear of the bracket and below the adjacent end of the screen, and a riffle table located longitudinally beneath the screen and trough and extending beyond the same, receiving the material from the former, said trough extend-

ing transversely of and beyond the side of the table, preventing the tailings from the screen falling upon said riffle table.

2. In a machine of the character described, 50 the combination with a supporting frame, of a bracket adjustably mounted thereon and having wheels, grooved wheels journaled on the frame, a rotary inclined screen having its lower end mounted on the wheels of the 55 bracket and its upper end provided with an annular flange that engages in the grooves of the other wheels, an arm carried by the bracket, a tailings receiving trough associated with the discharge of the screen and 60 having a pintle rotatably mounted in the arm, and separating means located longitudinally below the screen and the trough and receiving the material that passes through the screen, said trough being 65 located above the separating means between the ends thereof and swinging to positions to deliver on opposite sides of the separating means.

3. In a machine of the character described, 70 a separator comprising an open frame formed of longitudinal side bars and a center bar, cross bars connecting the center and side bars at intervals and having upstanding projections at their ends which are located 75 at the inner sides of the side bars and on opposite sides of the center bar, and a bottom for the apron body formed of sheet material extending from end to end of said body and having sections thereof disposed 80 in substantially horizontal relation, said sections extending from the lower edge of one cross bar to a position between the upper and lower edges of the next lower, and means for transversely shaking said separator. 85

In testimony that I claim the foregoing as my own, I have hereto affixed my signature in the presence of two witnesses.

OEN MEDARIS.
